UNITED STATES PATENT OFFICE.

FREDERICK W. LINAKER, OF DUBOIS, PENNSYLVANIA, ASSIGNOR TO THE VULCAN SOOT CLEANER CO., OF PITTSBURG, PA., OF DUBOIS, PENNSYLVANIA, A CORPORATION OF NEW JERSEY.

BOILER-FLUE-CLEANER SYSTEM.

1,144,553.

Specification of Letters Patent. Patented June 29, 1915.

Application filed March 8, 1915. Serial No. 12,793.

To all whom it may concern:

Be it known that I, FREDERICK W. LINAKER, a subject of the King of England, residing at Dubois, in the county of Clearfield and State of Pennsylvania, have invented certain new and useful Improvements in Boiler-Flue-Cleaner Systems, of which the following is a specification.

This invention relates to boiler flue cleaner systems, of the type employing a fluid-distributing pipe having a nozzle or nozzles or outlet or outlets for projecting a jet or jets or stream or streams of cleaning fluid among the tubes of a boiler to remove soot therefrom, the jet or jets or stream or streams of fluid being directed along radial lines or paths to adapt it to cover a great tube-surface area, and to project the cleaning fluid in planes parallel or approximately parallel 20 with the inclined or obliquely arranged tubes.

The present invention is especially designed for use in connection with boilers of the Stirling type in which banks of parallel inclined boiler tubes are employed and so disposed within the boiler setting as to present inclined tube surfaces to the action of the cleaning fluid. In this particular type of boiler, any fluid distributing pipes for the cleaning of the middle or upper portions of the tubes may be so disposed as shown in my companion application Serial No. 12,792, with relation to the usual baffles which obtain in this type of boiler, as to be protected 35 from the destructive heat zone of the fire chamber. It is not practical however, to employ a fluid distributing pipe of sufficient diameter to obtain a projection of cleaning fluid throughout the length of the bank of tubes, and consequently great difficulty has 40 been experienced in effectually cleaning the lower portions of the tubes in the bank. Since boilers of this type as constructed have no baffles adjacent the lower ends of 45 the bank or banks of tubes of which advantage may be taken for shielding and protecting the distributing pipe or pipes from the intense heat at this point, it is necessary to provide protecting means for the pipe or 50 pipes, as well as to provide means whereby the pipe or pipes may be supported and revolved in their supports, and to accomplish this in an efficient, simple and practical man-

ner is the main object of the present invention.

With the above and other objects in view, the invention resides in the novel construction, combination and arrangement of parts as will be hereinafter specifically described and then claimed, and in describing the invention in detail, reference will be had to the accompanying drawings showing practical embodiments of the invention without confining myself to the specific constructions shown and later described.

In the drawings, Figure 1 is a vertical sectional view of a boiler of the Stirling type showing one form or adaptation of my invention. Fig. 2 is a fragmentary view in similar section showing another adaptation of the invention. Fig. 3 is an enlarged detail side elevation of a portion of the boiler tubes, showing one form of support for the distributing pipe, and, Fig. 4 is a similar view showing another form of support.

A Stirling boiler of the type here shown has three inclined banks of tubes A, B and C, which at their upper ends connect respectively, with the steam drums D, E, and F, and at their lower ends with the water drum G. The bank A of tubes is directly exposed to the extreme heat of the furnace chamber H, and is particularly prone to a rapid accumulation of soot, the products of combustion being required to pass around the upper end of the baffle I that lies directly back of said bank of tubes A. Any permanently placed fluid distributing pipe placed below baffle I without protection from the extreme heat will soon burn out, it being understood that the cleaning agent is a fluid in the nature of steam or air and the pipe being normally empty. To prevent this, I provide, in the construction shown in Fig. 1, a short baffle 10 extending from the drum G at its lower end upwardly along the bank of tubes for some distance, sufficiently far to provide a heat protected zone 11 between the baffle 10 and the baffle I, said baffle 10 being located at or near the under row of tubes of the bank. In this protected zone 11, I place a fluid distributing pipe 12, usually provided with a plurality of jets or nozzles 14, the pipe being arranged transversely of the boiler-setting and bank of tubes, among the latter. This pipe is mounted for rotation,

any suitable means for rotating the same being employed, and, as will be understood, is connected to a suitable feed pipe (not shown) for supplying same with cleaning fluid.

5 A convenient and practical mode of supporting the pipe for rotation, in the forms shown in Figs. 1 and 3, is a clamp 15 clamped onto one of the tubes of the bank 10 and provided at its free end with a curved seat or saddle 16 in which the pipe is received; as many of these supports being provided transversely through the bank as may be necessary to effectually support the 15 pipe.

10 In the form shown in Figs. 2 and 4, in lieu of the short baffle 10, I build an extension or baffle 17 directly upon top of the bridge wall 18 which extension or baffle 20 is extended up near the lowermost row of tubes of the bank A and thus forms in back thereof, a protected zone 11 between the baffles 17 and I, in the same manner that such a zone is formed by the baffles 25 10 and I. In this zone, I place the distributing pipe 12 of the same form as above described and which is rotatable. A convenient and practical means for supporting the pipe in this construction is by 30 brackets 19 on top of the bridge wall 18, although other forms of supports may be used if desired.

35 By the constructions described, it will be observed that in each of them I have provided a protected zone in which the fluid distributing pipe is located and wherein it is fully protected from the extreme heat of the furnace in proximity to which the distributing pipe is located, the pipe being 40 protected from the flame of the fire coming in direct contact therewith, and consequently wholly protected from the damaging effects of such flame.

45 What I claim as new is:—
1. In a boiler tube cleaner system, the

combination with an inclined bank of tubes, and a relatively long baffle in back of said tubes, of a relatively short baffle at the lower end of the bank of tubes spaced from the longer baffle to form a heat protected 50 zone between the baffles, and a fluid distributing pipe rotatably mounted in said heat protected zone for projecting fluid onto said tubes for cleaning the same.

2. In a boiler tube cleaner system, the 55 combination with an inclined bank of tubes and a relatively long baffle in back of said tubes, of a relatively short baffle at the lower end of the bank spaced from the longer baffle to form a heat protected zone, 60 pipe supporting means within said zone, and a fluid distributing pipe rotatably supported in said pipe supporting means.

3. In a boiler tube cleaner system, the 65 combination with an inclined bank of boiler tubes, of a relatively short baffle at the lower end of the bank extending upwardly directly in back of the furnace chamber of the boiler to form a protected zone for the lower ends of the tubes that lie in back 70 of said baffle, and a fluid distributing pipe located in said zone and provided with nozzles for projecting cleaning fluid onto the lower portions of the tubes of said bank for cleaning the tubes.

75 4. The combination with a bank of inclined tubes, and a baffle located at the lower end of said bank, of means for cleaning the lower portion of said bank of tubes comprising a rotatable fluid distributing 80 pipe arranged transversely of the tubes adjacent said lower ends and in back of the baffle where it is protected from the heat of the furnace space.

85 In testimony whereof I affix my signature in presence of two witnesses.

FREDERICK W. LINAKER.
